BERNHARDT JORGENSEN, OF BEVERLY, MASSACHUSETTS, ASSIGNOR TO UNITED SHOE MACHINERY CORPORATION, OF PATERSON, NEW JERSEY, A CORPORATION OF NEW JERSEY.

MACHINE FOR SHAPING UPPERS OVER LASTS.

1,392,336.

Specification of Letters Patent.

Patented Oct. 4, 1921.

Application filed August 25, 1919. Serial No. 319,617.

To all whom it may concern:

Be it known that I, BERNHARDT JORGENSEN, a subject of the King of Denmark, residing at Beverly, in the county of Essex and State of Massachusetts, have invented 5 certain Improvements in Machines for Shaping Uppers Over Lasts, of which the following description, in connection with the accompanying drawings, is a specification, 10 like reference characters on the drawings indicating like parts in the several figures.

This invention relates to machines for shaping uppers over lasts, and has more particular reference to such machines as are 15 equipped with mean for engaging the marginal edge of the sole of the shoe on the bottom of the last to position said edge in the correct relation to the last, the term "sole" being used herein for convenience as in- 20 clusive of the insole of a welt or other type of shoe as well as of the sole of a turn shoe. The invention is herein shown as incorporated in a machine of a well known com- 25 mercial type having means for pulling the upper over the last and means for lasting the toe portion of the shoe, but it will be understood that the invention is not limited in utility to machines of this particular type nor to machines which include both pulling- 30 over and lasting means.

A feature of the invention consists in novel means of control for sole edge positioning or hold-down mechanism. In a prior Patent No. 1,379,924, granted upon my application on May 31, 1921, I have shown a 35 novel construction of edge hold-down mechanism applied to a power operated machine so controlled as to make a single stop between the beginning and the end of its cycle 40 of operations, the upper being pulled in the first stage of the cycle and wiped inwardly over the bottom of the sole in the second stage, and the hold-down members being withdrawn from operative position early in 45 the second stage of the cycle to make way for the advancing wipers which, as usual in machines of the well-known type illustrated, were arranged to be positioned preliminarily in engagement with the shoe in the intervening 50 period of rest. In many machines of this general type, however, the overwiping operation is not effected in the second stage of the cycle, but in an additional third stage following a second period of rest in which

the wipers are thus positioned manually. 55 The present invention provides a construction adapted for use in machines having a cycle of operations of this character, with the object of controlling the hold-down means in such manner as to maintain it in 60 effective engagement with the sole until after the wipers have been positioned manually in engagement with the shoe, thus insuring against displacement of the marginal edge of the sole by the pressure of the 65 wipers as they are adjusted in position to begin their subsequent overwiping operation. In the construction shown the hold-down members are maintained in operative position throughout the first two stages of 70 the cycle and are withdrawn from operative position substantially at the time of the final starting of the machine.

In another aspect, a feature of the invention consists in a novel combination of hold- 75 down mechanism and manual means to cause it to be withdrawn from operative position.

For the objects hereinabove set forth, among others, the construction shown comprises mechanism to render the starting 80 means for the machine effective to cause the withdrawal of the hold-down members independently of the power operation of the machine. In order to time the withdrawal of the members as desired, the illustrative ma- 85 chine is provided with an automatic control to render the starting means effective to cause such withdrawal only when said means is operated to initiate the final stage of the 90 cycle of the machine.

Still another feature of the invention consists in a novel construction designed to permit a hold-down member to adjust itself in conformity to the work, the construction shown comprising a member for engaging 95 the sole around its toe end and supporting means permitting the member to tip adjustably in conformity to the lengthwise contour or inclination of the sole.

While the invention is herein shown as 100 applied to a construction having characteristic features of the mechanism shown in said prior patent, it will be evident that the invention in its broader aspects is not limited in utility to constructions of that 105 particular character nor to machines which make any particular number of stops in the cycle.

The above and other features of the invention, including certain details of construction and combinations of parts, will now be described with reference to the accompanying drawings and pointed out in the claims.

In the drawings:

Figure 1 is a view in side elevation of the head portion of a pulling-over and lasting machine in which the invention is incorporated;

Fig. 2 is a transverse vertical section showing a portion of the hold-down mechanism;

Fig. 3 is a longitudinal vertical section, with parts in side elevation, illustrating more fully than Fig. 1 the relation of the hold-down members to the shoe;

Fig. 4 is a plan view of a portion of the means for effecting the release of the hold-down members;

Fig. 5 is a view of the same means in side elevation, with parts in vertical section on the line 5—5 of Fig. 4, and showing a portion of the treadle connections, and

Fig. 6 is a perspective view of the toe end hold-down member and its supporting means.

The machine herein shown, like the machine shown and described in said prior patent, has the usual toe and side grippers, the toe gripper comprising jaws 2 mounted on a gripper casing 4 and operated by a bar 6 connected to an updraw lever 8, and the side grippers comprising jaws 10, casings 12 and bars 14 connected to updraw levers 16. Only one of the side grippers with its operating connections is shown in Fig. 3, but it will be understood that similar mechanism is provided for pulling the upper at the other side of the shoe. The levers 8 and 16 are operated to close the gripper jaws and pull the upper by means characteristic of this well-known type of machine and not shown herein in detail. The shoe is positioned for the operation of the grippers by means of a sole rest 18 which receives a short downward swinging movement from the action of a cam 20 in engagement with a roll 22 on a sole rest carrier 24 to assist in the upper pulling operation. The machine has also the usual means for laying the upper over the margin of the sole at the toe end and at the opposite sides of the forepart and for fastening it by tacks or the like, the instrumentalities for performing these operations in the different locations being mounted upon side arms 26 and a front arm 28 (Fig. 1), these arms being moved inwardly toward the shoe to perform the overwiping operation and to position the tacking devices for the driving of the tacks. The overwiping operation at the toe end of the shoe is performed by end embracing wipers 30 on the front arm 28 which are advanced and closed

to wipe the upper into lasted position. The wipers 30 are carried by a supporting bracket 32 which is movable relatively to the arm 28 to permit the operator to advance the wipers preliminarily into engagement with the upper around the toe end of the shoe before the machine is started to perform the overwiping operation. The machine has also shoe supporting and holding devices mounted on side clamp arms 34 which are swung inwardly at the opposite sides of the shoe by connection to a cam operated slide 36.

The cycle of operations of the machine herein shown is performed in three successive stages under the control of clutch and brake mechanism which is arranged to be actuated by means of a treadle 38 and a treadle rod 40 to start the machine at the beginning of each stage of the cycle and is automatically operative to bring the machine to a stop at the end of each stage. The details of this mechanism are not herein illustrated but are fully shown and described in United States Letters Patent No. 791,986, granted on June 6, 1905 upon an application of R. F. McFeely. When the machine is started the first time by depression of the treadle the grippers are closed and the upper is pulled by the updraw movement of the gripper levers and by depression of the sole rest, whereupon the machine comes to a stop with the upper held under tension to permit its inspection and any necessary adjustment. When the machine is started the second time, the side clamp arms 34 are swung inwardly by the action of the slide 36 to hold and support the shoe for the subsequent overlaying and fastening operations. While the machine is at rest after this period of the cycle the operator is permitted to advance the wipers 30 and adjust them in contact with the upper and may also trip the toe gripper to cause it to release the upper. When the machine is started for the third time the overwiping and fastening operations are performed, the shoe is released, and the parts are returned to their starting positions.

The machine shown is also provided with sole edge hold-down mechanism which is similar in its general organization to the mechanism shown in the prior patent, and comprises members for engaging the marginal edge or feather of the sole at the toe end and at opposite sides of the forepart of the shoe. The toe end hold-down member comprises a plate 42 having a depending lip curved in substantial conformity to the curve of the edge of the sole around the toe, this plate being mounted upon an arm 44 pivotally connected to a slide 46 which is movable upwardly and downwardly along the inner side of the toe gripper bar and casing. The position of the member 42

lengthwise of the shoe is positively determined by connection of the arm 44 to an upwardly extending projection 48 on the sole rest 18, and when the hold-down is moved upwardly, as will be hereinafter described, a spring 50 swings the arm forwardly toward the gripper. Each side hold-down member comprises a plate 52 pivotally connected to a slide 54 which extends upwardly along the side gripper casing. As in the machine shown in said prior patent, the present machine has operating means for the several hold-down members to position them initially for engagement with the marginal edge of the sole when the shoe is presented in engagement with the sole rest, to move them downwardly in order to hold them in substantial engagement with the sole as the shoe is depressed by the sole rest, and subsequently to move them upwardly away from the sole to permit the overlaying and tacking operations to be performed. For these purposes a shaft 56 is provided having crank arms 58 and 60 which are connected respectively by means of links 62 to the slides 54 of the two side hold-down members, the arm 58 having an extension 64 connected by a link 66 to the slide 46 of the toe hold-down member. For moving the several hold-down members downwardly with the sole rest in the upper pulling operation, as well as for subsequently moving them downwardly after their release to return them again to their starting position, the shaft 56 is turned against the resistance of a spring 68 by mechanism fully shown and described in the prior patent and including a lever 70 connected to the gripper operating means, a link 72 (Fig. 1) and a crank arm 74 (Fig. 2), the latter being loosely mounted on the shaft 56 and having a clutch face arranged to coöperate with a similar face on a clutch hub 76 which is keyed to the shaft and is normally pressed by a spring 78 toward the hub of the arm 74.

It will be evident that as the parts are shown in Figs. 2 and 3 the hold-down members are held in their lowest position in engagement with the sole while the upper is held under tension by the grippers, the members being thus positioned by the positive connection of the shaft 56 to the crank arm 74 and its operating mechanism through the clutch hub 76. In order to cause the hold-down members to be withdrawn from operative position at the required time, it is necessary to disconnect the shaft 56 from the arm 74 and release it to the action of the spring 68 by moving the clutch hub 76 outwardly or toward the right (Fig. 2). For this purpose the flanged outer end of the hub 76 is engaged by rolls 80 mounted on a yoke-shaped member 82 which is fast on the upper end of a vertical rock shaft 84. The shaft 84 at its lower end is pro-

vided with a lever arm 86 through which movement is imparted to the shaft to retract the clutch hub and release the hold-down members.

In the present construction the arm 86 is arranged to be operated manually to effect the release of the hold-down members by mechanism connected to the treadle rod 40. This mechanism comprises a rod 88 connected at its lower end to a clamp 90 on the treadle rod and supporting at its upper end a sleeve member 92 which is pivoted transversely to the lower end of a rod 94, the latter extending loosely into a socket in a sleeve member 96 supported in bearings in a bracket 98 on the frame of the machine. Fast on the upper end of the member 96 is a cap 100 having a beveled periphery arranged to engage a roll 102 on the arm 86 and to swing the arm to effect the release of the hold-down members when the sleeve 96 is raised by the operation of the treadle rod. This cap is eccentrically mounted to permit adjustment for wear and to time properly the release of the hold-down members. In order to render the treadle rod and its connections comprising the members 88, 92 and 94 effective to raise the sleeve member 96, the member 94 carries a transverse pin 104 which is arranged to engage the lower end face of the member 96 at the required time to cause the member to be raised as the treadle is operated.

In order that the hold-down members shall not be released until the required time, which in a machine of the type herein shown is immediately prior to the operative movement of the wipers over the shoe, the machine has a lost motion connection to render the treadle ineffective to operate the arm 86 until it is depressed the third time to initiate the final stage of the cycle of operations. For this purpose the sleeve member 96 is provided with slots 106 in its opposite sides to receive the pin 104, and at the time of the first two actuations of the clutch to start the machine the member 96 is positioned with these slots in alinement with the pin 104 to permit the pin to move upwardly without raising the sleeve 96 and without affecting the hold-down members. Prior to the third or final treadling of the machine the member 96 is turned to carry its slots 106 out of alinement with the normal position of the pin 104 and permit the pin in the next operation of the treadle to engage the lower end of the sleeve and raise it. In the construction shown this is effected by the movement of the slide 36 which, as hereinbefore explained, is the means provided for swinging the clamp arms 34 inwardly in the second stage of the cycle of operations, this slide carrying an abutment member 108 which is arranged to engage the end of an arm 110 fast on the sleeve 96.

Since the pin 104 may be positioned within the slots 106 at the time when the slide 36 is operated immediately after the second depression of the treadle, a lost motion connection is provided between the rod 88 and the sleeve 92, comprising a pin 112 which projects from the rod through an arcuate slot 114 in the side of the sleeve member, this slot having a length corresponding to the extent of turning movement of the sleeve 96 effected by the slide 36. A spring 116 connected at its opposite ends respectively to the pin 112 and to a pin 118 on the member 92 holds the members 88 and 92 normally in the relation shown in Fig. 5 while permitting the member 94 to be turned with the sleeve 96 as above described. When the treadle is released by the operator after the machine has been started for the second time, the downward movement of the treadle rod effected by the spring 41 serves to withdraw the pin 104 from the slots 106, whereupon the spring 116 reacts to impart a reverse turning movement to the member 94, thus carrying the pin 104 out of alignment with the slots and into position for engagement with the lower end of the sleeve member 96 to raise it and effect the release of the hold-down members when the treadle is next operated. A spring 119 connected at its opposite ends to the abutment member 108 and the arm 110 serves to return the arm and the sleeve 96 to starting position when the slide 36 receives its return movement.

It will be evident from the foregoing description that in the construction herein provided the release of the hold-down members and their withdrawal from operative position is postponed until after the side clamp arms have been swung into engagement with the shoe and until after the operator has been permitted, during the pause in the operating cycle following such inward movement of the clamp arms, to advance the wipers and position them in engagement with the shoe in preparation for their subsequent operative movement over the shoe. The hold-down members, particularly the one at the toe end, are thus maintained in position to prevent any upturning of the marginal edge of the sole by pressure of the upper as the wipers are manipulated and adjusted in position against the shoe.

By reference to Fig. 6 it will be seen that in the present construction the connection between the toe hold-down plate 42 and the supporting arm 44 comprises a lug 120 which projects upwardly from the plate 42 and has a partially cylindrical contour for engagement in a bearing extending transversely of the arm 44, sufficient clearance being afforded between the lug and the plate and adjacent portions of the arm to permit the plate to tip about the transverse axis thus provided. This provision for tipping move-

ment has the advantage that the hold-down plate is permitted to adjust itself to the lengthwise contour or inclination of the sole and thus to seat itself firmly in engagement with the different portions of the marginal edge of the sole. The construction also permits the plate to be readily disengaged from the arm by sliding the member 120 lengthwise of its bearing in case it is desired to substitute a plate of different contour. In order to retain the plate in operative position on the arm, a spring pin 122 is provided, this pin being mounted in a slot in the arm and having a wedge shaped end arranged to engage in a V-shaped arcuate slot 124 in the member 120. When pressure is applied to slide the member 120 out of its bearing the pin 122 is wedged backwardly to release the member.

Having described the invention, what I claim as new and desire to secure by Letters Patent of the United States is:

1. In a machine of the class described constructed to perform its cycle of operations in successive stages after each of which the machine comes automatically to rest, the combination with starting means movable to initiate the operation of the machine at each stage of the cycle, of means for engaging the marginal edge of the sole of the shoe to position it relatively to the last in one stage of the cycle, and means operated by a subsequent movement of said starting means to cause said sole engaging means to be withdrawn from operative position independently of the power operation of the machine.

2. In a machine of the class described constructed to perform its cycle of operations in successive stages after each of which the machine comes automatically to rest, the combination with starting means movable to initiate the operation of the machine at each stage of the cycle, of a sole edge hold-down member, and means operated by one of the movements of said starting means to cause said member to be withdrawn from operative position independently of the power operation of the machine.

3. In a machine of the class described constructed to perform its cycle of operations in successive stages after each of which the machine comes automatically to rest, the combination with starting means movable to initiate the operation of the machine at each stage of the cycle, of means for engaging the marginal edge of the sole of the shoe to position it relatively to the last in one stage of the cycle, spring means for withdrawing said sole engaging means from operative position, and a tripping device arranged to be operated by a subsequent movement of said starting means to release the sole engaging means to the action of said spring means.

4. In a machine of the class described constructed to perform its cycle of operations in three successive stages with alternating periods of rest, the combination with starting means movable to initiate the operation of the machine at each stage of the cycle, of means for engaging the marginal edge of the sole of the shoe to position it relatively to the last during the first and second stages of the cycle, and means arranged to be operated by the movement of said starting means to initiate the third stage of the cycle to cause said sole engaging means to be withdrawn from operative position.
5. In a machine of the class described having means for pulling an upper over a last in one stage of the cycle of operations and means for laying the margin of the upper inwardly over the bottom of the last in a subsequent stage of the cycle following a period of rest, the combination with starting means movable to initiate the operation of the machine at each stage of the cycle, of means for engaging the marginal edge of the sole of the shoe to position it relatively to the last during the upper pulling operation, spring means for withdrawing said sole engaging means from operative position, and means arranged to be operated by the starting means in its movement to initiate the overlaying stage of the cycle to release said sole engaging means to the action of said spring means.
6. In a machine of the class described, the combination with means for pulling an upper over a last, shoe holding means movable into engagement with the shoe after the upper has been pulled, and overlaying means arranged to operate after said holding means has been moved to operative position, of means for engaging the marginal edge of the sole of the shoe to position it relatively to the last, and means arranged to be operated after the holding means has been moved into engagement with the shoe to cause said sole engaging means to be withdrawn from operative position.
7. In a machine of the class described constructed to perform its cycle of operations in three successive stages with alternating periods of rest and having means for pulling an upper over a last in the first stage, shoe holding means movable into engagement with the shoe in the second stage, and means for overlaying the margin of the upper in the third stage, the combination with a sole-edge hold-down member, of means for maintaining said member in engagement with the edge of the sole throughout the first and second stages of the cycle of operations, and means for subsequently causing said member to be withdrawn from operative position to make way for the operation of the overlaying means.
8. In a machine of the class described con-
- structed to perform its cycle of operations in three successive stages with alternating periods of rest and having means for pulling an upper over a last in the first stage, shoe holding means movable into engagement with the shoe in the second stage, and means for overlaying the margin of the upper in the third stage, the combination with starting means movable to initiate the operation of the machine at each stage of the cycle, of means for engaging the marginal edge of the sole of the shoe to position it relatively to the last in the first two stages of the cycle, and means operated by movement of said starting means to initiate the third stage of the cycle to cause said sole engaging means to be withdrawn from operative position.
9. In a machine of the class described, having means for pulling an upper over a last in one stage of the cycle of operations and wipers for laying the margin of the upper inwardly over the bottom of the last in a subsequent stage of the cycle following a period of rest in which the operator is permitted to position the wipers preliminarily in engagement with the shoe, the combination with a sole-edge hold-down member, of means for maintaining said member in engagement with the edge of the sole during the upper pulling operation, and means to cause said member to be withdrawn from operative position independently of the power operation of the machine after the wipers have been positioned in engagement with the shoe.
10. In a machine of the class described constructed to perform its cycle of operations in successive stages after each of which the machine comes automatically to rest, the combination with starting means movable to initiate the operation of the machine at each stage of the cycle, of means for engaging the marginal edge of the sole of the shoe to position it relatively to the last, mechanism arranged to be operated by one of the movements of said starting means to cause said sole engaging means to be withdrawn from operative position, and power operated means for rendering the starting means effective to operate said mechanism.
11. In a machine of the class described constructed to perform its cycle of operations in successive stages after each of which the machine comes automatically to rest, the combination with starting means movable to initiate the operation of the machine at each stage of the cycle, of means for engaging the marginal edge of the sole of the shoe to position it relatively to the last, mechanism arranged to be operated by said starting means to cause said sole engaging means to be withdrawn from operative position, means for positioning said mechanism normally in inoperative relation to

said starting means, and means automatically operative at a definite point in the cycle to position said mechanism in operative relation to the starting means.

- 5 12. In a machine of the class described constructed to perform its cycle of operations in successive stages after each of which the machine comes automatically to rest, the combination with starting means movable to 70
10 initiate the operation of the machine at each stage of the cycle, of means for engaging the marginal edge of the sole of the shoe to position it relatively to the last, mechanism arranged to be operated by said 75
15 starting means to cause said sole engaging means to be withdrawn from operative position, and means arranged to be operated in one stage of the cycle to render the starting means effective to operate said mechanism 80
20 when it is next moved to start the machine.

13. In a machine of the class described constructed to perform its cycle of operations in three successive stages with alternating periods of rest, the combination with 85
25 starting means movable to initiate the operation of the machine at each stage of the cycle, of means to engage the marginal edge of the sole of the shoe to position it relatively to the last in the first and second 90
30 stages of the cycle, mechanism arranged to be operated by said starting means to cause said sole engaging means to be withdrawn from operative position, means for positioning said mechanism normally in inoperative relation to the starting means, and means automatically operative in the second stage of the cycle to render the starting means effective to operate said mechanism 95
35 when it is next moved to start the machine. 100

40 14. In a machine of the class described constructed to perform its cycle of operations in successive stages after each of which the machine comes automatically to rest, the combination with starting means movable 105
45 to initiate the operation of the machine at each stage of the cycle, of means for engaging the marginal edge of the sole of the shoe to position it relatively to the last, mechanism arranged to be operated by one 110
50 of the movements of said starting means to cause said sole engaging means to be withdrawn from operative position, said mechanism including a lost motion connection to render the starting means normally 115
55 ineffective to cause the withdrawal of the shoe engaging means, and means automatically operative at a definite point in the cycle of operations to eliminate said lost motion. 120

60 15. In a machine of the class described constructed to perform its cycle of operations in successive stages after each of which the machine comes automatically to rest, the combination with starting means movable 125
65 to initiate the operation of the machine at

each stage of the cycle, of means for engaging the marginal edge of the sole of the shoe to position it relatively to the last, means comprising a spring for withdrawing said sole engaging means from operative 70
75 position, a tripping device to release said sole engaging means to the action of said spring, connections between said tripping device and the starting means including parts relatively movable to render the starting means normally ineffective to operate said device, and means automatically operative at a definite point in the cycle to move one of said parts relatively to another to render the starting means effective 80 to operate said device when it is next moved to start the machine.

16. In a machine of the class described constructed to perform its cycle of operations in successive stages with alternating periods of rest and having means for pulling an upper over a last in one stage and for overlaying the margin of the upper in a subsequent stage, the combination with starting means movable to initiate the operation 90
95 of the machine at each stage of the cycle, of means for engaging the marginal edge of the sole to position it relatively to the last during the upper pulling operation, mechanism arranged to be operated by said starting means to cause said sole engaging means to be withdrawn from operative position, means for positioning said mechanism normally in inoperative relation to said starting means, and means automatically operative prior to the overlaying stage in the cycle of operations to position said mechanism in operative relation to the starting means. 100

17. In a machine of the class described, the combination with means for pulling an upper over a last in one stage of the cycle of operations, means movable into holding relation to the shoe in the next stage, and means for overlaying the margin of the 105
110 upper in the third stage, of starting means movable to initiate the operation of the machine at each stage of the cycle, means for engaging the marginal edge of the sole of the shoe to position it relatively to the last in the first two stages of the cycle, mechanism arranged to be operated by said starting means to cause said sole engaging means to be withdrawn from operative position, means for positioning said mechanism normally in inoperative relation to the starting means, and means operative in the second stage of the cycle of operations of the machine to position said mechanism in operative relation to the starting means. 115
120

18. In a machine of the class described, the combination with means for working an upper over a last, of means for engaging the marginal edge of the sole of the shoe to position it relatively to the last, manu- 125
130

ally operative means to cause said sole engaging means to be withdrawn from operative position, and controlling means automatically operative to render said manual 5 means alternately effective and ineffective to cause the withdrawal of the sole engaging means.

19. In a machine of the class described, the combination with means for working 10 an upper over a last, of means for engaging the marginal edge of the sole of the shoe to position it relatively to the last, means comprising a spring for withdrawing said sole engaging means from operative position, a tripping device to release the sole 15 engaging means to the operation of said spring, manual means for operating said device including a lost motion connection normally effective to prevent the operation 20 of the device, and means automatically operative at a definite point in the cycle of operations of the machine to render said manual means effective to operate said device.

20. In a machine of the class described 25 constructed to perform its cycle of operations in successive stages after each of which the machine comes automatically to rest, the combination with starting means movable 30 to initiate the operation of the machine at each stage of the cycle, of means for engaging the marginal edge of the sole of the shoe to position it relatively to the last, power 35 operated mechanism for controlling said sole engaging means to maintain it in engagement with the sole, and means arranged to be operated by one of the movements of said starting means to release the sole engaging means from said power mechanism.

21. In a machine of the class described 40 constructed to perform its cycle of operations in successive stages after each of which the machine comes automatically to rest, the combination with starting means movable 45 to initiate the operation of the machine at each stage of the cycle, of means for engaging the marginal edge of the sole of the shoe to position it relatively to the last, power 50 operated mechanism for controlling said sole engaging means to maintain it in engagement with the sole, means arranged to be operated by one of the movements of said starting means to release the sole engaging means from said power mechanism, 55 and power operated means for rendering said starting means alternately effective and ineffective to cause such release.

22. In a machine of the class described 50 constructed to perform its cycle of operations in successive stages after each of which the machine comes automatically to rest, the combination with starting means movable 55 to initiate the operation of the machine at each stage of the cycle, of means for engaging 60 the marginal edge of the sole of the shoe

to position it relatively to the last, power operated mechanism for controlling said sole engaging means to maintain it in engagement with the sole, mechanism connected to said starting means to effect the release of 70 said sole engaging means from the power mechanism and including parts arranged for relative movement to render the starting means normally ineffective to cause such release, and power means for moving one of 75 said parts relatively to another to render the starting means in its next operative movement effective to cause the release of the sole engaging means.

23. In a machine of the class described, 80 the combination with means for working an upper over a last, of means for engaging the marginal edge of the sole of the shoe to position said edge relatively to the last, power 85 operated mechanism for controlling said sole engaging means to maintain it in engagement with the sole, and manually operated means for causing said sole engaging means to be withdrawn from operative position independently of the power operation of the 90 machine.

24. In a machine of the class described, the combination with means for working an upper over a last, of means for engaging the marginal edge of the sole of the shoe 95 to position said edge relatively to the last, power operated mechanism for controlling said sole engaging means to maintain it in engagement with the sole, means comprising a spring for withdrawing said sole 100 engaging means from operative position, and a manually operated tripping device for releasing said sole engaging means to the action of said spring.

25. In a machine of the class described, a 105 hold-down member curved in substantial conformity to the edge contour of the end of a sole and having an edge portion constructed for engagement with the marginal edge of the sole on its bottom face outside of the 110 rib or shoulder of the sole, a support for said member, and a connection between said member and support constructed to permit the member to tip to adjust itself in conformity to the lengthwise contour or inclination 115 of the sole.

26. In a machine of the class described, a hold-down member curved in substantial 120 conformity to the edge contour of the end of a sole and having an edge portion constructed for engagement with the marginal edge of the sole on its bottom face outside of the rib or shoulder of the sole, a support for said member, and a projection on said member swiveled in said support to permit the member to tip about an axis extending laterally 125 of the shoe in response to pressure of the sole against it.

27. In a machine of the class described, a 130 hold-down member curved in substantial con-

formity to the edge contour of the end of a sole for engagement with the marginal edge of the sole on its bottom face, a support for said member, means comprising a swivel connection between said member and its support to permit the member to tip about an axis extending laterally of the shoe and to be disconnected from the support by movement in the direction of said axis, and

a retaining device arranged to hold said member normally in operative position on its support and to yield automatically as said member is moved to disconnect it from the support.

In testimony whereof I have signed my name to this specification.

BERNHARDT JORGENSEN.
